UNITED STATES PATENT OFFICE.

AUGUST Z. SNYDER, OF TURTLE CREEK, PENNSYLVANIA.

NECKTIE-TYING DEVICE.

1,235,390.

Specification of Letters Patent. Patented July 31, 1917.

Application filed September 27, 1916. Serial No. 122,543.

To all whom it may concern:

Be it known that I, AUGUST Z. SNYDER, a subject of the King of England, residing at Turtle Creek, in the county of Allegheny and State of Pennsylvania, have invented 5 new and useful Improvements in Necktie-Tying Devices, of which the following is a specification.

This invention relates to devices for 10 tying neckties of the four-in-hand type and supporting them in position for use in connection with a turn-down collar.

The object of the invention is to provide 15 a device to facilitate the tying of the necktie, and to obviate the necessity of retying the same each time it is used.

A further object is to provide means for readily adjusting the tie in position upon the collar.

20 With the above objects in view the invention consists of a holder formed of a single piece of spring wire, bent into shape to form a curved supporting member, a bar parallel with the supporting member for holding 25 the tie off from the collar, and a spring arm provided with a notch for engagement with the collar button.

In the drawings:

Figure 1 is a front elevation of the holder 30 secured in position, the tie being shown thereon by dotted lines;

Fig. 2 is a detached front elevation of the holder with the tie in position thereon;

Fig. 3 is a rear elevation of the same;

35 Fig. 4 is a vertical sectional view illustrating the bar for supporting the tie from the rear and giving the knot a puffed appearance; and

Fig. 5 is a detail view of the holder.

40 The improved holder shown in the accompanying drawings consists of curved parallel members, forming a loop, comprising an upper tie supporting bar 1 and a lower parallel bar 2. The lower bar extends a suf-

ficient distance to practically form a closed 45 loop, one end of the loop being formed by a curved continuation 3 of the member 1. The wire is then bent to form an angularly disposed spring member 4, and is formed with a notch 5. The triangular shaped 50 member is provided with a free end 6.

In use, the knot is tied upon the bar 1, the holder being concealed behind the knot as shown in Fig. 2 of the drawings. As 55 illustrated in Figs. 3 and 4, the bar 2 lies directly behind the knot, below the bar 1, and acts to press the knot outward to prevent the tie from assuming a flat position against the front of the collar. As shown in Fig. 1, the holder is secured in position 60 by passing the ends of the loop beneath the turn-down front of the collar and snapping the notch of the spring member 4 in position behind the collar button. The member 4 being provided with a free end and made of 65 spring metal, is easily and quickly adjusted in position and securely held therein.

From the foregoing it will be seen that the invention provides a holder formed of a single piece of bent wire, upon which the 70 knot may be tied, and which permits of the tie being quickly adjusted to the collar.

Having thus described my invention, I claim:

A neck tie holder formed from a single 75 piece of spring wire and comprising a curved member arranged to lie behind the tie, said member being bent to form a substantially parallel tie supporting bar, said bar being further bent to form, together 80 with the first mentioned bar, an open ended loop and a spring arm formed by a continuation of the tie supporting bar, said arm being provided near its free end with a notch for engagement with the collar button. 85

In testimony whereof I affix my signature.

AUGUST Z. SNYDER.
